Primary Examiner — Selina Sikder(74) *Attorney, Agent, or Firm* — Lucas & Mercanti, LLP;
Klaus P. Stoffel(57) **CLAIM**

The ornamental design for a remote control, as shown and described.

DESCRIPTION

FIG. 1 is a perspective view of the remote control of the present invention;
FIG. 2 is a top view thereof;
FIG. 3 is a bottom view thereof;
FIG. 4 is a left view thereof;
FIG. 5 is a right side view thereof;
FIG. 6 is a front view thereof;
FIG. 7 is a rear view thereof;
FIG. 8 is a perspective view of a second embodiment thereof;
FIG. 9 is a top view thereof;
FIG. 10 is a bottom view thereof;
FIG. 11 is a left view thereof;
FIG. 12 is a right side view thereof;
FIG. 13 is a front view thereof; and,
FIG. 14 is a rear view thereof.

1 Claim, 6 Drawing Sheets(56)
